UNITED STATES PATENT OFFICE.

FREDERIC E. IVES, OF WOODCLIFFE-ON-HUDSON, NEW JERSEY.

SELF-PLAYING MUSICAL INSTRUMENT.

No. 908,865.

Specification of Letters Patent.

Patented Jan. 5, 1909.

Application filed October 31, 1908. Serial No. 460,395.

To all whom it may concern:

Be it known that I, FREDERIC E. IVES, a citizen of the United States, residing in Woodcliff-on-Hudson, New Jersey, have invented certain Improvements in Self-Playing Musical Instruments, of which the following is a specification.

My invention relates to that class of self-playing pianos or organs or detached player mechanisms in which the perforated music sheet is combined with an indicating pointer intended to follow a guide line on the music sheet representing changes in tempo, expression or the like, the object of my present invention being to permit such location of the indicating pointer in respect to the music sheet that it will not interfere with the ready introduction or removal of the latter, while, at the same time, there will be a close optical juxtaposition of the moving end of the pointer and that portion of the guide line on the music sheet which is passing over the tracker board. This object I attain in the manner hereinafter set forth, reference being had to the accompanying drawing, in which—

Figure 1 is a vertical section of sufficient of a self-playing piano to illustrate my present invention, and Fig. 2 is a front view of the same looking in the direction of the line of vision indicated in Fig. 1.

In the drawing, 1 represents part of the front panel of a piano and 2 part of the casing in the rear of the same which contains the tracker board 3 and music sheet rolls 4. Pivotally mounted upon the casing 2 or other convenient support above the music rolls is an indicating pointer 5, which may be so connected to the expression or tempo controlling devices of the piano as to move in unison therewith. I have not considered it necessary to show any such connection in the present case, as the particular connection employed forms no part of my present invention. I may, however, refer to my Letters Patent No. 901,906, dated October 20th, 1908, as illustrating one means whereby an indicator pointer may be connected to the expression controlling devices of the piano.

In my patented device the indicating pointer projected over the music sheet so that the movable end of the pointer could be caused to closely follow the guide line indicating change of expression at the point where said guide line passed over the tracker board but such projection of the pointer

over the music sheet is objectionable because the pointer has to be moved and held out of the way whenever the music sheet has to be changed and must be restored to its operative position after a music sheet has been inserted into position.

I now find that by the use of a suitable reflecting device I can locate the indicating pointer away from the music sheet and still produce an optical juxtaposition of the movable end of the pointer and the guide line on the music sheet where the latter passes over the tracker board. Such a reflecting device is illustrated at 6 in the drawing and consists of a mirror of any desired width or length, this mirror being carried at its ends by one or more arms 7 pivotally mounted, by preference, upon the structure of the piano in such manner that the mirror may either be adjusted to the operative position shown by full lines in Fig. 1, or swung up into the position shown by dotted lines in said figure, so as to offer no obstacle to the free insertion or removal of the music roll and the application of the end of the music sheet to the winding roll, the mirror being, in this respect, much more convenient to move than the indicating pointer itself, since the movement of the latter is complicated by the attachments whereby the indicating movement is imparted to it.

When the mirror is adjusted to the position shown by full lines in Fig. 1, it occupies a position just beyond the line of vision falling upon the music sheet where the same passes over the tracker board 3 and bears such relation to the moving lower end of the pointer 5 that the latter is reflected to the eye in immediate juxtaposition to this portion of the music sheet as indicated in Fig. 2, consequently the movements of the indicator pointer may be caused to closely follow the guide line on the music sheet at the point where it passes over the tracker board and the expression, tempo, or other control can thus be closely regulated.

In the drawing my device is shown as suitably attached for use when the tracker board is below the level of the eyes. It is evident that if the tracker board should be placed above the level of the eyes, then the indicating pointer should be placed below the mirror and the mirror faced downward. It is evident also that the device is applicable to the so-called outside players, as well as to pianos

or organs containing the playing devices. Prismatic or lenticular prismatic reflectors may, if desired, be substituted for the plane mirror shown in the drawing.

5 I claim:

1. The combination of the tracker board and music sheet carrying devices of a self-playing musical instrument, with an indicating pointer relatively remote from the tracker board, and means for visually juxtaposing the moving end of the indicator pointer and that portion of the music sheet which is passing over the tracker board.

2. The combination of the tracker board and music sheet carrying devices of a self-playing musical instrument with an indicating pointer located out of the way of the music sheet and a mirror located in front of the latter in such relation to the line of vision falling upon the same where it passes over the tracker board that the moving end of the

indicating pointer will be reflected in juxtaposition to such line of vision.

3. The combination of the tracker board and music sheet carrying devices of a self-playing musical instrument with an indicating pointer located out of the way of the music sheet and a mirror located in front of the latter in such relation to the line of vision falling upon the same where it passes over the tracker board that the moving end of the indicating pointer will be reflected in juxtaposition to such line of vision, said mirror being pivotally mounted so that it can be moved out of the way. 35

In testimony whereof, I have signed my name to this specification, in the presence of two subscribing witnesses.

FREDERIC E. IVES.
